UNITED STATES PATENT OFFICE

RUDOLPH F. LINDOW, OF MILWAUKEE, WISCONSIN, ASSIGNOR TO CHAIN BELT COMPANY, OF MILWAUKEE, WISCONSIN, A CORPORATION OF WISCONSIN

CONCRETE MIXING APPARATUS

Application filed December 10, 1930. Serial No. 501,397.

This invention relates to concrete mixing apparatus and more particularly to apparatus of this character which comprises two or more mixing machines operated in tandem, and has for its principal object to provide an efficient means in the form of an auxiliary chute for transferring the partially mixed concrete from the usual discharge chute of one mixer into the charging skip of the adjacent mixer.

A further object of the invention is to provide an apparatus of this character which will be simple in construction, comparatively inexpensive to manufacture and which may be readily incorporated into new machines or with equal facility attached to mixers already in use.

With the above and other objects in view which will appear as the description proceeds, the invention consists in the novel details of construction and combinations of parts more fully hereinafter disclosed and particularly pointed out in the appended claims.

Referring to the accompanying drawings forming a part of this specification in which like reference characters designate like parts in all the views:—

Figure 1 is a diagrammatic side elevational view of a portion of two concrete mixers of a well known paving type operated in tandem, one of which is provided with an auxiliary discharge chute constructed and arranged in accordance with the present invention;

Figure 2 is a fragmentary end elevational view of the mixer shown in Figure 1 which is provided with the said auxiliary chute; and

Figure 3 is a fragmentary side elevational view of the said mixer illustrating the auxiliary chute in its nonreceiving position.

Referring more particularly to the said drawings the numerals 5 and 6 indicate generally a pair of concrete mixers of the well known paving type positioned to operate in tandem in accordance with recently developed practice along this line, whereby increased production of completely mixed con-

crete is secured as is well understood by those skilled in the art.

The mixer 5 is provided with the usual charging skip, not shown, and with the frame work 7, mixing drum or receptacle 8 and discharge chute 9 all of which are of the ordinary and well known construction. The said mixer 5 may be provided with the usual bucket and boom distributing apparatus but this is preferably omitted since in the present method of operation it is not necessary and if present must be swung out of the way. The mixer 6, is likewise of ordinary construction, having the usual mixing drum, discharge chute and bucket and boom distributing apparatus, not shown, and the usual charging skip 10 which is adapted to be raised and lowered in order to elevate materials into the drum in the well known manner.

In the tandem method of operation it is customary to charge the cement, aggregates and water into the drum of the first mixer in the usual manner where they are partially mixed for a period of approximately one half the total time required to produce the complete mix. At the end of this reduced mixing period the partially mixed concrete is discharged from the drum of the first mixer into the skip of the second mixer and elevated thereby into the drum of the second mixer, where the mixing period is completed, after which the completely mixed concrete is discharged into the distributing apparatus of the second mixer and distributed thereby in the usual manner. This method of operation requires that the charging skip of the second mixer when lowered occupy a position where it will receive the partially mixed concrete discharged into the discharge chute of the first mixer. Because of certain structural dimensions, which cannot be well changed in present mixers of the paving type, it is not practical to position the two mixers sufficiently close together for the skip of the second mixer to occupy this required position with relation to the discharge chute of the first mixer without interference with the said chute during the swing of the skip, and it is therefore necessary to provide an addition-

100

al or sub-chute, or other means for insuring that the partially mixed concrete from the first drum is deposited into the skip of the second mixer.

5 The present invention provides such an auxiliary chute indicated at 11 which may be supported by the side arms or plates 12 which are pivoted as at 13 in frame members or brackets 14 which are rigidly secured to 10 the framework 7 of the first mixer 5. The said auxiliary chute 11 is adapted to occupy either the position illustrated in Figure 1, which is its operative position, or the position illustrated in Figure 3 which is its non-re- 15 ceiving position and to which position it must be moved in order to permit of the elevation of the skip 10 of the second mixer as will be readily apparent from Figure 1. In other words, when the skip 10 is elevated its outer- 20 most edge must swing through the arc of a circle which intersects the auxiliary chute 11 when in the position shown in Figure 1 and in order to avoid contact of the parts the said auxiliary chute should be automatically 25 moved from the position shown in Figure 1 to that shown in Figure 3.

In the present instance this automatic movement is accomplished through the medium of a pair of arms 15, secured to the mem- 30 bers 12 below the pivot 13, each of which carries at its innermost end a suitable weight 16. The said weights are of such value that they will more than counterbalance the weight of the auxiliary chute 11 and its as- 35 sociated parts so that the latter will always be urged toward the position illustrated in Figure 3 through the medium of the said weights. In order to overcome the action of these weights and to move the auxiliary chute 40 from its non-receiving to its receiving position shown in Figure 1, the arms 15 are ex- tended outwardly into the path of the de- 45 scending skip 10 and are preferably provided with suitable plates or shoes 17 which are engaged by the edge portions of the skip 10 in its descent as will be readily understood. The weight of the said skip is, of course, sufficient to overcome the action of the weights 16 and the parts will therefore be automati- 50 cally moved through the medium of the de- scending skip from the position shown in Figure 3 to that shown in Figure 1 where the auxiliary chute 11 is in position to receive the partially mixed concrete from the dis- 55 charge chute 9 and insure that it is deposited into the skip 10.

After such transfer of the charge has been effected, as the skip 10 is elevated to discharge the partially mixed concrete into the drum 60 of the mixer 6, the weights 16 will swing the auxiliary chute 11 out of the path of the ascending skip as will be readily understood.

While one form of the invention has been illustrated and described, it is obvious that 65 those skilled in the art may vary the details

of construction as well as the precise arrangement of parts without departing from the spirit of the invention, and therefore it is not wished to be limited to the above disclosure except as may be required by the claims. 70

What is claimed is:

1. In a concrete mixer, the combination with a frame, a mixing receptacle and a discharge chute, of an auxiliary chute pivotally mounted on said frame for oscillatory movement to and from a position in which it may receive concrete from said discharge chute; and a weighted arm connected with said auxiliary chute, adapted to normally urge said auxiliary chute toward its non-receiving position, said arm having an extension to which a force may be applied to move said auxiliary chute to its receiving position. 75

2. The combination with a plurality of concrete mixers, one of which is provided with a swinging drum-charging skip and another of which has a drum-discharging chute, of a movable auxiliary chute for receiving concrete from said discharge chute and discharging it into said charging skip, said auxiliary chute having means engageable by said charging skip for moving it from a non-receiving to a receiving position relative to said discharge chute. 80

3. The combination with a plurality of concrete mixers, one of which is provided with a swinging drum-charging skip and another of which has a drum-discharging chute, of a movable auxiliary chute for receiving concrete from said discharge chute and discharging it into said charging skip, said auxiliary chute having means engageable by said charging skip for moving it from a non-receiving to a receiving position relative to said discharge chute; and means for moving said auxiliary chute to non-receiving position when said first named means is disengaged by said charging skip. 90

4. The combination with a pair of concrete mixers disposed in tandem, one of which is provided with a swinging drum-charging skip and the other of which has a drum-discharging chute, of a pivoted auxiliary chute for receiving concrete from said discharge chute and discharging it into said charging skip; means connected to said auxiliary chute, engageable by said skip as it is lowered, for moving said auxiliary chute from a non-receiving to a receiving position relative to said discharge chute; and weights for moving said auxiliary chute back to non-receiving position as said skip is raised. 100

In testimony whereof I affix my signature.
RUDOLPH F. LINDOW.
